(57) **CLAIM**

The ornamental design for a ring toss target board, as shown and described.

DESCRIPTION

FIG. 1 is a front view of a ring toss target board showing my new design;

FIG. 2 is a rear view of the ring toss target board;

FIG. 3 is a right side view of the ring toss target board;

FIG. 4 is a left side view of the ring toss target board;

FIG. 5 is a top view of the ring toss target board;

FIG. 6 is a bottom view of the ring toss target board; and, FIG. 7 is a top front side perspective view of the ring toss target board.

The broken lines in the figures are illustrative of environmental structure forming no part of the claimed design.

1 Claim, 4 Drawing Sheets(56)
